Primary Examiner — John Windmuller*Assistant Examiner* — Steven J Czyz(74) *Attorney, Agent, or Firm* — Hogan Lovells US LLP(57) **CLAIM**

The ornamental design for a valet/clothes stand, as shown and described.

DESCRIPTION

FIG. 1 is a perspective view of a valet/clothes stand showing the design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The elements depicted in broken lines form no part of the claimed design.

The broken lines in FIG. 7 are for the purpose of illustrating the attachment mechanisms and form no part of the claimed design.

1 Claim, 6 Drawing Sheets(56)
